(57) **CLAIM**

The ornamental design for insulated container padding, as shown and described.

DESCRIPTION

FIG. 1 is a left-side, top perspective view of insulated container padding in an unassembled configuration showing my new design.

FIG. 2 is a right-side, bottom perspective view of my new design shown in FIG. 1.

FIG. 3 is a top view of my new design shown in FIG. 1.

FIG. 4 is a bottom view of my new design shown in FIG. 1.

FIG. 5 is a left-side view of my new design shown in FIG. 1.

FIG. 6 is a right-side view of my new design shown in FIG. 1.

FIG. 7 is a front-end view of my new design shown in FIG. 1.

FIG. 8 is a rear-end view of my new design shown in FIG. 1.

FIG. 9 is a left-side, top perspective view of my new design shown in FIG. 1 in an assembled configuration.

FIG. 10 is a right-side, bottom perspective view of my new design shown in FIG. 9.

FIG. 11 is a top view of my new design shown in FIG. 9.

FIG. 12 is a bottom view of my new design shown in FIG. 9.

FIG. 13 is a left-side view of my new design shown in FIG. 9.

FIG. 14 is a right-side view of my new design shown in FIG. 9.

FIG. 15 is a front-end view of my new design shown in FIG. 9; and,

FIG. 16 is a rear-end view of my new design shown in FIG. 9.

1 Claim, 14 Drawing Sheets
